MACHINE FOR INSERTING FASTENINGS.

1,280,209.

Specification of Letters Patent.

Patented Oct. 1, 1918.

Application filed December 10, 1915. Serial No. 66,185.

To all whom it may concern:

Be it known that I, GEORGE GODDU, a citizen of the United States, residing at Winchester, in the county of Middlesex and 5 State of Massachusetts, have invented certain Improvements in Machines for Inserting Fastenings, of which the following description, in connection with the accompanying drawings, is a specification, like reference characters on the drawings indicating like parts in the several figures.

This invention relates to machines for inserting fastenings. By way of illustration the invention is herein shown as embodied 15 in a machine of the type disclosed in United States Letters Patent No. 490,621, granted January 24, 1893, on an application of Louis Goddu, for inserting screw threaded fastenings in the soles of boots and shoes.

20 In machines of the type disclosed in said Letters Patent the wire carrying spindle and the shaft from which the several mechanisms of the machine are driven are maintained continuously and uninterruptedly in operation and manually controlled means are provided for suspending the operation of the wire feeding mechanism by holding it out of operative relation to its actuator when it is not desired to insert fastenings. In the operation of machines of this type as heretofore constructed, however, difficulty has been experienced by reason of the fact that there 25 was no certainty as to the time in the cycle of operations of the machine when the wire feeding would be resumed with the result that frequently, upon manipulation of the manually controlled means to establish operative relation between the wire feeding mechanism and its actuator, for example, to

40 initiate the insertion of fastenings upon a given piece of work, either a fastening shorter than the proper length for the given thickness of work would be inserted or occasionally the machine would fail entirely to 45 insert a fastening in the first fastening location. Various attempts have heretofore been made to provide satisfactory wire feeding suspension mechanisms for machines of the illustrated type but so far as known none 50 of these mechanisms has gone into general use.

One of the objects of the present invention is to provide a simple and efficient mecha-

nism for controlling the establishment of operative relation between the wire feeding mechanism and its actuator to the end that invariably the first fastening inserted after an initiation of wire feeding movement will be of the full length required by the thickness of the work, which mechanism will be reliable, economical to manufacture and capable of embodiment readily in machines of said type at comparatively low cost. In accordance with this object the preferred embodiment of the invention comprises mechanism constructed and arranged to insure that the initiation of the operation of the wire feeding mechanism will occur only when the wire feeding mechanism and its driving means are relatively positioned so that the first wire feeding movement imparted to the wire feeding mechanism thereafter will be a complete feeding movement regardless of when the means for controlling the suspension of the wire feeding mechanism is manipulated to effect such suspension.

Another disadvantage in machines of the type above mentioned as heretofore constructed consists in the fact that such machines have had no provision for discontinuing the operation of the work feeding means when the wire feeding mechanism is inoperative. This has resulted in unnecessary wear and tear of the work feeding mechanism and furthermore it has imposed upon the operator the necessity of taking care to prevent feeding movement of the work whenever it was not desired to insert fastenings.

Another object of the invention is to provide work feeding mechanism suspending means which will be adapted to be embodied readily in a machine of the type disclosed in said Letters Patent and which will suspend the operation of the work feeding mechanism whenever the wire feeding mechanism is inoperative.

A still further disadvantage encountered in the use of machines of the said type has resulted from the liability of the work supporting horn to drop from work clamping position before the last fastening desired has been completely inserted. In machines of this type heretofore movement of the horn out of work clamping position has been de-

pendent entirely upon release of the horn raising treadle, the construction being such that whenever the horn raising treadle was released the horn immediately dropped from work clamping position. In consequence the operator could not determine with any certainty the proper time in the cycle of operations of the machine to release the horn especially by reason of the comparatively high speed at which such machines are run.

An important object of the invention is to insure that the last fastening desired in a given piece of work is completely inserted before the horn is permitted to move out of work clamping position, and to this end the illustrated machine is provided with means constructed and arranged to maintain the horn locked in work clamping position until such predetermined time in the cycle of operations as will insure the complete insertion of the last fastening regardless of when the treadle is released, the horn being automatically released in predetermined time relation to the suspension of the wire feeding mechanism. In the illustrated construction the final release of the horn is controlled by the usual mechanism for intermittently depressing the horn to permit the work to be fed.

30 Preferably, and as shown, the means for suspending the operation of the wire feeding mechanism and establishing operative relation between the wire feeding mechanism and its actuator, as well as the means 35 for suspending the operation of the work feeding mechanism, may be controlled by the horn raising treadle so that merely by depressing a single treadle the operator may initiate the operation of the wire feeding 40 and work feeding mechanisms and raise the horn to work clamping position, while upon release of that treadle the operation of these mechanisms is suspended and the horn is moved from work clamping position in 45 proper time relation.

Although the invention is herein disclosed with especial reference to embodiment in a machine of the general type shown and described in the above-mentioned Letters Patent and various objects and features of the invention have been discussed with particular reference to machines of this type, it is to be understood that the invention is not intended to be limited thereby since it is contemplated that the invention as a whole or 55 various features thereof may have other uses.

These and other objects and features of the invention will be apparent from the following detailed description read in connection with the accompanying drawings and the various novel features of the invention are set forth in the appended claims.

In the drawings.—

Fig. 7 is a view similar to Fig. 6 of a part of the mechanism shown therein when the horn is in work clamping position; and

Fig. 8 is a perspective view showing the horn controlling mechanism.

The machine in which a preferred form of the invention is shown as embodied is substantially the same as that disclosed in said above mentioned Letters Patent except as herein fully described in detail and reference may be had to said Letters Patent for a more detailed description of parts herein illustrated but not fully described.

The machine has a base 2 which supports a head 4 having mounted therein a vertically disposed spindle 6 which carries at its upper end the wire from which the fastenings are formed. The spindle 6 is continuously rotated by a belt passing over a pulley 8 on the upper end of the spindle and over idlers 10 to a driving pulley 12 mounted in the base 2 of the machine and arranged to be clutched to a driven pulley 14 by a suitable clutch connected through the rod 16 to a clutch operating treadle 18. The spindle is provided with a worm which engages worm gears 20 upon the forward ends of lateral shafts 22 one of which carries the various cams for effecting the wire feeding, wire severing, work feeding and horn depressing operations. Preferably these cams are formed to cause two operations of their respective mechanisms during one complete rotation of the cam shaft 22.

The wire is fed downwardly through the spindle 6 by a wire feeding and inserting sleeve 24 surrounding the spindle 6 and slidably mounted on guideways on the machine frame, the lower end of said sleeve being provided with wire gripping members 26 which operate to seize the wire as said sleeve is moved downwardly. The sleeve 24 is reciprocated in the frame to feed a length of wire and insert it into the work by a wire feed lever 28 pivoted at 30 in the machine frame and having two forwardly projecting arms each carrying segmental gears 32 which engage respective racks 34 formed on a yoke attached to the upper end of the sleeve 24. An upwardly extending arm 36 of the lever 28 carries a cam roll 38 which

is engaged by a wire feeding edge cam 40 on one of the continuously rotating lateral shafts 22. The wire feed lever 28 is normally held in position to be actuated by the 5 cam 40 to move the feeding sleeve downwardly by a comparatively strong spring 42 (Fig. 1) and a rod 44 the lower end of which bears on a lug provided on a rearwardly extending arm 46 of the lever 28. After the 10 proper length of wire is inserted in the work the wire is severed by wire severing knives mounted in the lower ends of two knife carrying arms 45 which have a common fulcrum on a shaft 47 mounted in the machine 15 frame.

In order that the wire inserted in the work may correspond with the thickness of the work clamped between the horn 48 and the fastening inserting mechanism, the extent 20 of feeding movement imparted to the wire feed lever 28 by the wire feeding cam 40 is automatically varied. This is accomplished by providing on the horn 48 a laterally extending arm 50 to the outer end of 25 which is attached a measuring rod or leg 52 projecting upwardly through a guide 54 on the frame. This rod serves as a variable stop to determine the amount of movement in one direction of a coöperating rod 56 the 30 lower end of which is also located in the guide 54 and having its upper end pivotally secured at 58 to the end of the rearwardly extending arm 46 of the wire feed lever 28. It will thus be seen that as the horn 48 is 35 moved into position to clamp the work the measuring rod 52 is correspondingly moved in the guide 54 relatively to the coöperating rod 56 and the wire feed lever 28 can assume a position, relatively to its actuating cam 40 determined by the position of the measuring rod 52 in accordance with the thickness of the work.

When the machine is being used to insert fastenings the spindle 6 and the two lateral 45 shafts 22, one of which carries the various cams, are continuously rotated and the insertion of fastenings is interrupted by suspending the wire feeding mechanism.

When the wire feeding mechanism is operated 50 to cause the insertion of fastenings to be resumed it is of considerable importance that the wire feeding lever 28 be in such operative relation to its continuously rotating actuator as to provide an initial fastening 55 of the length required by the thickness of the work clamped by the horn. In accordance with the present invention, means are provided for automatically suspending the operation of the wire feeding mechanism 60 upon the release of the treadle by the operator and for automatically releasing the wire feeding suspending means at predetermined times in the cycle of operations of the machine. The illustrated means for suspending 65 the operation of the feeding mecha-

nism comprises a block 60 slidably mounted in the frame and having a slot 62 through which projects the lower end of the measuring rod 56 to which a sleeve stop 63 is adjustably secured by the set nut 64, the stop 70 being of such diameter as to allow it to pass through the slot 62. The block 60 is normally maintained in position for the stop 63 to become seated on a shelf 66 provided at the rear end of the slot, immediately after 75 the wire feed lever has reached its limit of feeding movement by a spring pressed plunger 68 located in the frame and having its end bearing upon a lug 70 projecting from the side of the block 60. In order to 80 release the wire feeding suspending means automatically at predetermined times in the cycle of rotation of the cam 40 or at times when the amount of wire fed will correspond to the thickness of the work being operated 85 upon the block 60 is automatically removed from under the stop 63 to permit it to pass through the slot 62 into a position determined by the position of the measuring leg 52, as shown in Fig. 5 by an arm 72. The 90 rear end of the arm 72 is pivoted to a stud 74 on one arm 76 of a bell crank lever 104 and at its other end is provided with a slot 75 through which projects a vertically disposed rod 78 bolted to a yoke member 80 95 which is mounted for vertical movement in guideway 82 in the frame. The slot 75 allows for the play of the arm when it is in inoperative position. A spring 84 surrounding the rod 78 holds the forward end of the 100 lever 72 near the upper end of the rod. The yoke member 80 is secured to the upper end of a rod 86 the lower end of which is connected to one arm 87 of a treadle lever 88 fulcrumed on the shaft 90. A strong compression spring 92 surrounding the rod 86 and interposed between a guideway 94 on the frame and a stop 96 on the rod acts normally to keep the forward end of the treadle raised. The arm 72 is provided with 105 a projecting catch 98 adapted to engage the projecting lug 70 on the block and to move the block inwardly against the tension of the spring pressed plunger 68 after the arm has been moved into operative position by the 110 treadle. The movement of the arm 72 is effected through connections with the mechanism for actuating the wire severing arms 45 to sever the length of wire inserted in the work. The wire severing cam 114 is provided with toes 112 which are adapted to engage a hardened steel plate 110 attached to one end of a lever 106 fulcrumed on the stud 108 and connected at its opposite end through the link 100 to one arm of the bell crank lever 104 fast on the shaft 47. The forward end of the shaft 47 is provided with gears, not shown, which mesh with coöperating gears on the wire severing arms 45 to cause an approach of the arms to sever the wire, when 115 120 125 130

the shaft 47 is partially rotated as fully described in said above mentioned patent. It will thus be seen that as the bell crank 104 is oscillated to cause the operation of 5 the wire severing arms 45 the arm 72 which is attached to the arm 76 of the bell crank may also be moved rearwardly to remove the block 60 from under the stop 63 on the coöperating measuring leg 56. A depending 10 arm 115 on the lever 106 engages a cushioning pad 116 located in a recess in the frame of the machine to reduce the shock and vibration incident to the return of the lever 106 into position to be engaged by the toes 15 112. In order to maintain the block 60 in inoperative or suspended position after having been initially moved into such position by the arm 72 the yoke 80 is provided with a latch 118 pivoted on a stud 120 and sup- 20 ported at its forward end in substantially horizontal position by a plug 122 seated on a spring 124 located in a recess in the yoke. The forward end of the latch 118 is adapted to engage a lip 126 projecting from the 25 bottom face of the block 60 and hold the block against the tension of the spring pressed plunger 68 during the time the yoke is in its operative position and the fastenings are being inserted.

30 In machines of this type heretofore constructed the work is fed after each insertion of a fastening by a feed wheel which is intermittently rotated by a continuously rotating actuator. When the work feeding mechanism is thus kept in motion after the fastening inserting operation has been stopped the parts are subjected to excessive wear. Also when the work is presented to the machine to receive fastenings the feed 35 wheel is not in timed relation to the insertion of the initial fastening; therefore the work often becomes displaced. The work feeding mechanism herein disclosed is automatically suspended simultaneously with 40 the stopping of the insertion of fastenings and is automatically rendered operative upon the initial movement of the wire feed mechanism to insert a fastening. The illustrated preferred embodiment of work feeding mechanism comprises a feed wheel 128 having a beveled gear on its under side which meshes with a gear on the outer end of the shaft 130, the opposite end of the shaft being provided with a pinion 132.

45 This pinion is loosely mounted on the shaft 130 and is engaged by a rack on one arm 134 of a two armed lever fulcrumed on the shaft 136, the other arm 138 of said lever being arranged to be engaged by a cam roll 140 on the lower end of a lever 142 fulcrumed on a stud 144 in the machine frame. The upper end of this lever is provided with a cam roll 145 which is adapted to travel in a cam track in the wire feed cam 40. A 50 spring pressed plunger located in a recess

in a lug 148 on the side of the arm 134 and bearing against the frame tends to cause the lever to follow the movement of the lower end of the lever 142 and return the work feeding lever to its normal inoperative position or to the left in Fig. 3. A pawl 150 carried by the pinion 132 is adapted to engage a coöperating ratchet wheel 151 fast on the shaft 130 to effect rotation of the feed wheel in work feeding direction when the 55 arm 134 is moved in operative direction. When the arm 134 is returned to its inoperative position under the influence of the spring plunger in the lug 148 the pawl rides over the teeth on the ratchet wheel 151. The feed wheel is automatically locked in its inoperative position by a latch 152 pivoted on a stud 154 and adapted to position itself under a projection 156 on the hub of the two armed lever. The latch 152 is provided with a tail piece 158 which is engaged by a spring pressed plunger 160 acting normally to position the latch under the projection 156. In order that the work feeding mechanism may be automatically released from its locking means or from the latch 152 in timed relation to the insertion of the initial fastening in the work the measuring rod 56 is provided with an offset 60 arm 162 carrying at its lower end an adjustable stop 164 arranged to contact with the tail 158 of the latch and move it out of the way of the projection 156 during downward movement of the rod 56 preliminary to the insertion of the initial fastening. The latch 152 is retained in unlocking position during the fastening inserting operation by a latch 166 pivoted on the yoke 80 in position to hook over the tail piece 158 of the latch 152.

65 As above suggested, an important feature of the invention is the provision of an improved organization of mechanism whereby a single treadle may be utilized to render the machine operative to insert fastenings 70 and to effect a movement of the horn into work clamping position and maintain said horn in such position until after the final fastening has been completely inserted in the work. In the illustrated embodiment of this 75 feature of the invention, horn 48 is carried upon the upper end of a horn supporting shaft 168 attached at 169 to the forward end of a lever 170 fulcrumed on a stud 172 in the base of the machine. The other end of this 80 lever is connected through toggle links 174 and 176 and a connecting link 178 to the curved outer end 180 of the main treadle lever 88. One end of the toggle link 174 is pivotally secured at 179 to the hooked end 182 of a lever 184 also fulcrumed on the stud 172 and provided with a member 186 having a bore in which is received the lower end of a rod 188 forming part of the automatic horn release and work thickness compensat- 85 90 95 100 105 110 115 120 125 130

ing mechanism 190. The work thickness compensating mechanism herein shown is of well known construction and is fully shown and described in United States Letters Patent No. 383,455, granted May 29, 1888, on application of L. Goddu. A spring 192 surrounds the rod 188 and is confined between the machine frame and the collar 194 on said rod, the spring acting normally to maintain the hooked end 182 of the lever in its lowermost position. The horn is periodically depressed to permit the work to be fed after each insertion of fastenings through the horn depressing and work thickness compensating mechanism which is actuated by a cam (not shown) on the main shaft of the machine to raise the curved end 182 of the lever 184 about its fulcrum 172 which in turn lifts the straightened toggle 174 and 176 and oscillates the lever 170 about its fulcrum to permit the horn to drop the desired distance. The horn is prevented from immediately moving into work receiving position when the treadle is released by the operator until after the complete insertion of the fastening then being inserted. This is effected by means which are rendered operative through the release of the horn to allow the work to be fed after the final fastening has been completely inserted. The illustrated means comprises a latch 196 pivoted on the stud 172 and having its forward end arranged to fall into engagement with a shoulder on a block 198 secured to the side of the connecting link 178 as the link is moved upon depression of the treadle to straighten the toggle 174 and 176 as illustrated in Fig. 7. The forward end of this latch moves with the block 198 and maintains the toggle straightened at all times during the normal operation of the machine, that is, while the treadle 88 is depressed. When the operator removes his foot from the treadle to stop the insertion of fastenings a finger 204 pivoted at 206 on the frame is allowed to swing into engagement with teeth 202 provided on the rear face of a tail piece 200 of the latch thus locking the latch against oscillation about its pivot. The treadle is thus prevented from assuming its inoperative position owing to the toggle being held in straightened position by the latch, and therefore, the horn remains in work clamping position.

When the lever 184 is oscillated by the horn release to depress the horn sufficiently to permit the work to be fed after the final fastening has been inserted in the work, the raising of the toggle 174, 176 allows the block 198 to free itself from the latch 196 which is locked by the finger 204 whereby the toggle instantly becomes broken and the horn assumes its work receiving position.

The operation of the machine hereinabove described is as follows: The spindle 6 and

the main shafts 22 of the machine are set in continuous rotation by the depression of the treadle 18. Upon depression of the foot treadle 88 the toggle 174, 176 is caused to be straightened and the horn raised into work clamping position. Movement of the treadle 88 also raises the yoke 80 through the rod 86 and positions the arm 72 into operative relation to the block 60 which in its inoperative position, as shown in Fig. 4, is located under the stop 63 on the rod 56 thus holding the feed lever 28 out of engagement with the wire feed cam 40. The adjustable stop 208 on the treadle lever 88 has also engaged the tail 207 of the finger 204 and allowed the latch 196 to fall into engagement with the block 198 on the link so that the toggle is locked in straightened position. As one of the toes 112 on the cam 114 engages the plate 110 on the end of the lever 106 after the arm 72 has been raised into operative position by the treadle it moves the lever 72 through the connections 100, 104 and 76 in a direction to withdraw the block 60 from under the stop 63. The wire feed lever 28 is immediately moved under the influence of the spring 42 and rod 44 in a direction to move the cam roll 38 into position to be engaged by the second portion of the cam 40 when it comes into position during the next half cycle of rotation of the cam. It will be seen that the wire feeding lever 28 is not in engagement with the wire feeding cam 40 to insert a fastening during the first half rotation of the shaft 22 and the cams carried thereby and that the utilization of the first operation of the wire severing cam, which operation occurs immediately after the first half rotation of the shaft 22 has been completed, to release the block 60 from under the stop 63 enables the wire feed lever to position itself relatively to the cam 40 at such time as will allow the succeeding half of the wire feeding cam to impart its maximum throw to the wire feed lever 28. The amount of feed imparted to the lever 28 however is determined by the thickness of work clamped by the horn which thickness corresponds to the position the measuring leg 52 has assumed in the guide 54. The raising of the yoke 80 through the rod 86 upon the depression of the treadle causes the latch 118 to engage the lip 126 of the block 60 and thus maintain the block 60 in released position, that is, in position to allow the stop 63 on the measuring leg 64 to pass through the slot 62 in the block. The downward movement of the rod 56 to position the wire feed lever relatively to its actuating cam 40 also causes the adjustable stop 164 to contact with the tail 158 of the latch 152 and move it from under the projection 156 of the work feed arm. The latch 152 is held clear of the projection 156 by the latch 166 pivoted on the yoke 80 and

brought into position to engage the tail 158 of the latch when the yoke is raised by the initial depression of the treadle. After each fastening has been inserted the horn is depressed a sufficient distance to permit the work to be fed through connections 190 and 188 between a cam not shown and the rear end of the lever 184. This connection with the rear end of the lever 184 turns the lever 10 about its fulcrum 172 and causes its forward end 182 to raise the rear end of the lever 170 through the straightened toggle member 174, 176 which in turn lowers the forward end of the lever 170 to which the horn is attached. The latch 196 at this time moves with the toggle 174, 176 and prevents it from being broken. The work is fed forward into position to receive the next fastening by the feed wheel 128 which is rotated by connections 130, 134 and 138 and lever 142 to the cam 40. The work feed lever is then returned to its normally inoperative position under the influence of the spring pressed plunger in the lug 148, the pawl 150, riding over the teeth on the ratchet 151 so as to prevent the rotation of the shaft 130 during the return of the parts. When the operator removes his foot from the treadle 88 to stop the insertion of fastenings 20 the lost motion in the treadle mechanism allows the treadle to rise sufficiently to remove the stop 208 from engagement with the tail 207 of the finger 204 whereby the finger immediately drops into engagement with the teeth 202 provided on the latch member. The latch, being locked, is prevented from following the next movement of the toggle members as they are raised by the horn release after the final fastening has been inserted. The block 198 being free of the latch 196 allows the toggle to be broken, whereby the horn is lowered into work receiving position and the treadle 88 raised into normal position. Since the horn release mechanism is positively controlled in 40 timed relation to the fastening inserting mechanism, or in other words, since the horn release is never operated until after the final fastening has been inserted, it will be noted that by causing the treadle mechanism to be positively locked until such release occurs insures the complete insertion of the final fastening regardless of the time at which the operator releases the treadle to 50 stop the machine. Simultaneously with the complete release of the treadle the block 60, under the influence of the spring 68 may position itself under the stop 63 of the measuring leg 56 to suspend further operation of the wire feeding lever, since the wire feeding lever is at this time at the limit of its feeding movement. Also the latch 152 immediately snaps under the projection 156 thus suspending both wire feeding means 60 and the work feeding means.

Having described my invention, what I claim as new and desire to secure by Letters Patent of the United States is:—

1. In a machine for inserting fastenings, wire feeding mechanism, wire severing mechanism, means for suspending the operation of one of said mechanisms, and means operated by the other of said mechanisms to render said first named mechanism operative. 75
2. In a machine for inserting fastenings, wire feeding mechanism, wire severing mechanism, means for suspending the operation of said wire feeding mechanism, and means operated by said wire severing mechanism to render said wire feeding mechanism operative. 80
3. In a machine for inserting fastenings, wire feeding mechanism, wire severing mechanism, automatic means for suspending the operation of said wire feeding mechanism, and connections from said automatic means to said wire severing mechanism operated automatically by said wire severing mechanism to render said wire feeding mechanism operative, and means for rendering said automatic means operative. 85
4. In a machine for inserting fastenings, wire feeding mechanism, wire severing mechanism, means for suspending the operation of the wire feeding mechanism, and means operated automatically by said severing mechanism to render said wire feeding mechanism operative constructed and arranged to release said wire feeding mechanism only when the parts of said wire feeding mechanism are positioned to effect the maximum wire feeding movement for which the machine is set to insure the insertion of a full length fastening upon resumption of operation of the wire feeding mechanism. 95
5. In a machine for inserting fastenings, wire feeding mechanism, wire severing mechanism, means for suspending the operation of said wire feeding mechanism, means operated automatically by said wire severing mechanism to render said wire feeding mechanism operative, and manually operated means for rendering said automatic means operative. 105
6. A machine for inserting fastenings comprising a continuously rotating wire carrying spindle, a shaft continuously driven from said spindle, wire feeding means operated from said shaft, a member tending normally to maintain said wire feeding mechanism disconnected from said shaft, wire severing mechanism including an operating cam on said shaft, lever connections from said cam to said member operated by said cam to withdraw said member into inoperative position to restore operative connection between the wire feeding mechanism and said shaft, and a treadle operatively 110
- 120
- 125
- 130

connected with said lever connections to position said connections in operative relation to said member.

7. In a machine for inserting fastenings, 5 wire feeding mechanism, a continuously and uninterruptedly rotated power driven shaft for said wire feeding mechanism, automatic means tending to disconnect said wire feeding mechanism from said shaft, a treadle, a 10 member connected with the treadle for operative movement upon movement of the treadle in one direction, a normally inoperative device connected with said member for movement into operative relation to said 15 automatic means upon operative movement of said member, means operating automatically to cause said device to render said automatic means inoperative to restore operative connection between said wire feeding mechanism and said shaft when said device has 20 been brought into operative relation thereto, and a latch for holding said automatic means in inoperative position while said wire feeding mechanism is connected to said 25 shaft, said latch being carried by said member for movement therewith into operative position.

8. In a machine for inserting fastenings, wire feeding mechanism, a power driven 30 shaft for operating said wire feeding mechanism, automatic means acting normally to disconnect said wire feeding mechanism from said shaft, a power driven normally inoperative device adapted to be brought into 35 operative relation to said automatic means to effect operative connection between said wire feeding mechanism and said shaft, and a manually controlled member connected with said device for moving said device into 40 operative relation to said automatic means.

9. In a machine for inserting fastenings, wire feeding mechanism, a power driven shaft for operating said wire feeding mechanism, automatic means acting normally to 45 disconnect said wire feeding mechanism from said shaft, a power driven normally inoperative device operable when in operative relation to said automatic means to move said automatic means to inoperative 50 position so as to effect operative connection between said wire feeding mechanism and said shaft, a manually controlled member for moving said normally inoperative device into operative relation to said automatic means, and a latch for holding said automatic means in inoperative position while said device is in operative relation to said 55 automatic means.

10. In a machine for inserting fastenings, 60 wire feeding mechanism, a power driven shaft for operating said wire feeding mechanism, automatic means tending to disconnect said wire feeding mechanism from said shaft, a power driven normally inoperative 65 device operable when in operative relation

to said automatic means to move said automatic means to inoperative position to effect operative connection between said wire feeding mechanism and said shaft, a manually controlled member for moving said device into operative relation to said automatic means. 70

11. In a machine for inserting fastenings, a continuously rotating wire carrying spindle, a shaft continuously driven from said spindle, wire feeding mechanism operated from said shaft, means for suspending the 80 operation of said wire feeding mechanism, means for rendering said wire feeding mechanism operative, a work support movable between work receiving position and work clamping position, and a single means 85 for controlling the operation of said last named means and moving said work support into work clamping position.

12. In a machine for inserting fastenings, wire feeding mechanism, a power driven 90 shaft for operating said mechanism, means for disconnecting the wire feeding mechanism from its said shaft, means for reconnecting said feeding mechanism with said shaft, a work support movable between work 95 receiving and work clamping positions, a single means for controlling the operation of said last named means and for moving said work support into work clamping position, and means for locking said work support in work clamping position. 100

13. In a machine for inserting fastenings, a continuously and uninterruptedly rotated power driven shaft, wire feeding mechanism normally connected to said shaft to be operated by said shaft, means for disconnecting said wire feeding mechanism from said shaft, means for reconnecting said feeding mechanism with said shaft automatically at predetermined times, a work support movable between work receiving and work clamping positions, and a single manually operated means for controlling the operation of said automatic means and moving said work support. 110

14. In a machine for inserting fastenings, a continuously and uninterruptedly rotated power driven shaft, wire feeding mechanism normally connected to said shaft to be operated by said shaft, means for disconnecting said wire feeding mechanism from said shaft, means for reconnecting said feeding mechanism with said shaft automatically at predetermined times, a work support movable between work receiving and work clamping positions, a treadle, connections from said treadle to said work support for raising the work support into work clamping position, and connections from said treadle to said automatic means for render- 115 120 125 130

ing said automatic means operative when the work support is raised.

15. In a machine for inserting fastenings, wire feeding mechanism, a continuously and uninterruptedly rotated power driven shaft, means secured to said shaft for operating said wire feeding mechanism, automatic means tending to disconnect said wire feeding mechanism from its operating means 5 and to lock said wire feeding mechanism out of engagement with said operating means, continuously driven connections between said shaft and said wire feeding mechanism operating when permitted to reconnect said wire feeding mechanism with its operating means, a work support movable between work receiving and work clamping positions, a treadle, connections from said treadle to said work support for 10 raising the work support and to said reconnecting means for rendering said reconnecting means operative when the work support is raised into work clamping position, and a latch operated by said treadle for maintaining said locking means in inoperative 15 position while the treadle is in raised position.

16. In a machine for inserting fastenings, wire feeding mechanism, operating means 20 for said wire feeding mechanism, means for disconnecting said wire feeding mechanism from its operating means, means operating automatically at predetermined times to reconnect said wire feeding mechanism with its operating means, a work support movable 25 between work receiving and work clamping positions, connections between said work support and the wire feeding means operating to predetermine variably the times 30 when said automatic means is effective to reconnect the wire feeding mechanism with its operating means, said connections being controlled by movement of said work support according to changes in a characteristic 35 of the work being operated upon, a treadle, and connections from said treadle to said work support and to said automatic reconnecting means for raising the work support 40 and rendering said reconnecting means operative when the work support is raised.

17. In a machine for inserting fastenings, wire feeding mechanism, means for suspending the operation of the wire feeding mechanism at predetermined times, work feeding mechanism, and means for suspending the operation of the work feeding mechanism operatively connected with the means for suspending the wire feeding mechanism to cause the operation of said mechanisms to 55 be suspended substantially simultaneously.

18. A machine for inserting fastenings comprising a continuously rotating wire carrying spindle, a shaft continuously driven from said spindle, wire feeding means operated from said shaft, means for suspending 60

the operation of the wire feeding mechanism at predetermined times, work feeding mechanism, and means for suspending the operation of the work feeding mechanism operatively connected with the means for suspending the wire feeding mechanism to cause the operation of said mechanisms to be suspended substantially simultaneously. 70

19. In a machine for inserting fastenings, wire feeding mechanism, means for normally locking said wire feeding mechanism in inoperative position, work feeding mechanism, means for normally locking said work feeding mechanism against operation, and separate manually controlled means for 75 automatically releasing the wire feeding mechanism and the work feeding mechanism.

20. In a machine for inserting fastenings, wire feeding mechanism, means for operating said wire feeding mechanism, means for normally locking said operating means in inoperative position, work feeding means, operating means for said work feeding means, means for normally locking the operating means for said work feeding means in inoperative position, separate means operating automatically to release the operating means for the wire feeding mechanism and the operating means for the work feeding mechanism, and a single manually operated means for controlling the operation 80 of said releasing means. 90

21. In a machine for inserting fastenings in boots and shoes, fastening inserting mechanism, work feeding mechanism, continuously driven operating means for said work feeding mechanism, operating connections between said means and said work feeding mechanism comprising a member movable relatively to said work feeding 100 mechanism, means for locking said member against operative movement, and means operated automatically at predetermined times to render said member operative to operate 105 said work feeding mechanism. 110

22. In a machine for inserting fastenings, fastening inserting mechanism for inserting fastenings successively in a piece of work, work feeding mechanism operable to feed the piece of work between successive operations of said fastening inserting mechanism, means acting normally to lock said work feeding mechanism against work feeding movement, and means operating automatically to release said locking means at predetermined times in the operation of the machine. 115

23. In a machine for inserting fastenings, work feeding mechanism, a continuously rotating actuator for said mechanism, means operated automatically to lock said work feeding mechanism in inoperative relation to said actuator, means operated automatically at predetermined times to place said work feeding mechanism in operative relation 120 125 130

65

to said actuator, and means constructed and arranged to maintain said locking means inoperative whenever the work feeding mechanism is in said operative relation.

5 24. In a machine for inserting fastenings, work feeding mechanism, a continuously rotating actuator for said mechanism, means operating automatically to lock said work feeding mechanism against operative movement, means operated automatically at predetermined times to render said work feeding mechanism operative, and a manually controlled device for maintaining said locking means in inoperative position when said 10 work feeding mechanism is operative.

15 25. In a machine for inserting fastenings, wire feeding mechanism, wire severing mechanism, means for feeding the work intermittently to present successive selected 20 portions of the work for the operation of said mechanisms, means for suspending the operation of said work feeding mechanism, and means controlled by said wire severing mechanism to render said work 25 feeding mechanism again operative.

26. In a machine for inserting fastenings, wire feeding mechanism, means for feeding the work successively to present selected portions of the work for the operation of 30 said mechanism, means operated automatically to suspend the operation of said work feeding and said wire feeding mechanisms, means operated automatically by said wire feeding mechanism to render said work 35 feeding mechanism again operative, and manual means for controlling the operation of said last named automatic means.

27. In a machine for inserting fastenings, a continuously driven shaft, wire feeding 40 mechanism driven from said shaft, a work support movable between work receiving and work clamping positions, means for locking the work support in work clamping position, and devices for disconnecting said 45 wire feeding mechanism from said shaft and releasing said work support in predetermined time relation to prevent premature movement of the work support from work clamping position.

50 28. In a machine for inserting fastenings, a continuously driven shaft, wire feeding mechanism driven from said shaft, a work support movable between work receiving and work clamping positions, a treadle, connections from the treadle to the work support to move the work support into work clamping position, means controlled by said treadle to lock the work support in work clamping position, and devices operating to 55 disconnect the wire feeding mechanism from its driving shaft and to release the work support in predetermined time relation regardless of when the treadle is released.

60 29. In a machine for inserting fastenings, wire feeding mechanism, continuously driven

means for operating said wire feeding mechanism, a work support movable between work receiving and work clamping positions, means for locking said work support in work clamping position constructed 70 and arranged to release said work support only between the completion of a wire feeding movement and the initiation of a succeeding wire feeding movement, and connections between said work support and said 75 wire feeding mechanism constructed and arranged to suspend the operation of said wire feeding mechanism in predetermined time relation to movement of the work support from work clamping position. 80

30. In a machine for inserting fastenings, wire feeding mechanism, continuously driven means for operating said wire feeding mechanism, a work support movable between work receiving and work clamping 85 positions, a treadle, connections from the treadle to the work support to move the work support between said positions, means operated by the treadle to lock the work support in work clamping position constructed 90 and arranged to release the work support only during an interval between wire feeding movements, and means operating automatically to disconnect said wire feeding mechanism from its driving means upon return movement of the treadle to move the work support from work clamping position. 95

31. In a machine for inserting fastenings, wire feeding mechanism, continuously driven means for operating said wire feeding mechanism, a work support movable between work receiving and work clamping positions, a treadle, connections from the treadle to the work support to move the work support between said positions, means for locking the work support in work clamping position constructed and arranged to release the work support only during the interval between successive wire feeding movements, and means operated by said treadle to suspend 105 the operation of the wire feeding mechanism upon return movement of the treadle. 110

32. In a machine for inserting fastenings, wire feeding mechanism, continuously driven means for operating said wire feeding mechanism, a work support movable between work receiving and work clamping positions, a treadle, connections from the treadle to the work support to move the work support into work clamping position, means operated by 115 said treadle to lock the work support in work clamping position, said means being constructed and arranged to release said work support only after the completion of a wire feeding movement, and connections between said treadle and said wire feeding means constructed and arranged to suspend the operation of said wire feeding means during return movement of the treadle. 120 125

33. In a machine for inserting fastenings, 130

- fastening inserting mechanism, a work support movable between work receiving and work clamping positions, a treadle, connections from the treadle to the work support to move the work support into work clamping position, means for periodically depressing the work support to permit the work to be fed, and means controlled by said work support depressing means operating to prevent premature movement of the work support from work clamping position upon release of the treadle and to render said fastening inserting mechanism inoperative.
34. In a machine for inserting fastenings, fastening inserting mechanism, a work support movable between work receiving and work clamping positions, treadle operated means for moving said work support into work clamping position, means for periodically moving said work support into positions between said work receiving and clamping positions, and devices controlled by said last named means for preventing premature movement of the work support from work clamping position upon release of the treadle and for rendering said fastening inserting mechanism inoperative.
35. In a machine for inserting fastenings, wire feeding mechanism, a work support movable between work receiving and work clamping positions, means for locking the work support in work clamping position, and coöperating devices connecting said wire feeding mechanism and said work support constructed and arranged to render said wire feeding mechanism inoperative and to release the work support in predetermined time relation to prevent premature movement of the work support from work clamping position.
36. In a machine for inserting fastenings, wire feeding mechanism, a work support movable between work receiving and work clamping positions, means for locking the work support in work clamping position constructed and arranged to release the work support only in an interval between successive wire feeding movements, and connections between the work support and said wire feeding mechanism constructed and arranged to render the wire feeding mecha-

nism inoperative upon movement of the work support from work clamping position.

37. In a machine for inserting fastenings, wire feeding mechanism, a work support movable between work receiving and work clamping positions, a treadle, a toggle between said treadle and said work support for raising the work support into work clamping position upon depression of the treadle to straighten the toggle, automatic means for periodically depressing the straightened toggle to lower the work support to permit the work to be fed, a latch for locking the toggle in straightened position, and a dog operated upon release of the treadle to cause said latch to unlock the toggle upon the succeeding elevation of the toggle by said automatic means.

38. In a machine for inserting fastenings, wire feeding mechanism, means for suspending the operation of said wire feeding mechanism, work feeding mechanism, means distinct from the wire feeding mechanism suspension means for suspending the operation of the work feeding mechanism, a work support, and manually controlled means for raising the work support from work receiving position to work clamping position and relieving the wire feeding mechanism and the work feeding mechanism from control by said suspending means.

39. In a machine for inserting fastenings, wire feeding mechanism, means for suspending the operation of the wire feeding mechanism, work feeding mechanism, means distinct from the means for suspending the operation of the wire feeding mechanism and operable to suspend the operation of the work feeding mechanism, a work support, means for moving the work support, and connections between the work support moving means and the suspending means for the wire feeding and work feeding mechanisms constructed and arranged to cause the operation of the wire feeding and work feeding mechanisms to be suspended when the work support is lowered to work receiving position.

In testimony whereof I have signed my name to this specification.

GEORGE GODDU.
